UNITED STATES PATENT OFFICE.

JAMES M. GARVEY, OF APPLETON, WISCONSIN, ASSIGNOR TO GARVEY-WEYENBERG CONSTRUCTION COMPANY, OF APPLETON, WISCONSIN, A CORPORATION.

SUBGRADE PLANER.

Application filed January 6, 1922. Serial No. 527,422.

To all whom it may concern:

Be it known that I, JAMES M. GARVEY, citizen of the United States, residing at Appleton, in the county of Outagamie and

5 State of Wisconsin, have invented certain new and useful Improvements in Subgrade Planers, of which the following is a specification.

My invention comprises a machine for 10 smoothing, scraping, or planing road subgrades in preparation thereof for the building of an appropriate road surface. A machine of this type is especially desirable and useful for operation upon the sub-grades of 15 roads to be concreted or otherwise paved or resurfaced.

A unique and important feature of the invention resides in the combination of my road planing and scarifying means with a 20 mixing machine, such as is commonly now known as a concrete paver, the mixing machine being of a portable type and having equipment for loading, mixing and depositing concrete aggregates upon the sub-grade. 25 By uniting my planing and scarifying instrumentalities with the mixing machine, I obtain a single machine which is capable of doing the work heretofore necessitating two separate machines, with resultant saving of 30 expense of construction, and of greater importance, cost of operation.

Respecting my planing and scarifying means per se it is notable that I employ a novel construction of carrier or frame 35 adapted to be supported upon, and to operate along the usual road forms or rails provided at opposite sides of a roadbed, and between which a concrete pavement is deposited and molded, so to speak. My carrier or frame is equipped with suitable scraping and scarifying devices, together with special 40 connecting devices by which the carrier is attached to the mixing machine so as to be propelled thereby as the mixing machine progresses. The attaching means between 45 the planing and scarifying machine and the mixing machine are peculiar in that they are especially designed so as to accommodate for slight lateral shifting, relatively, between the planer and the mixing machine truck to 50 which it is attached. Likewise, said attachment means accommodates for relative verti-

cal movements of these two machines incident to inequalities in the surface over which they pass, and other possible conditions of 55 service.

The foregoing, together with the other incidental features of construction constitute primarily novel phases of my invention, which will be more fully understood upon 60 reference to the detailed description in conjunction with the annexed drawings, in the latter of which:

Figure 1 is a plan view of a combined mixing machine, a planer and scarifier, embodying my invention, the body of the mixing machine being omitted so as to show the relation of the planer and scarifier relative to the traction supporting means of the 65 main or mixing machine.

Figure 2 is a front view of the planer and scarifier showing the relation of the same to the front wheels of the paver or mixer.

Figure 3 is a view in elevation of the carrier or frame of the planer, and illustrating more fully the arrangement and construction of the scraping or cutting blades.

Figure 4 is a side elevation showing primarily the parts illustrated in Figure 1 together with a portion of the loading skip 80 that forms a part of the paving machine.

Figure 5 is a diagrammatic side view showing the invention applied to what is known as a paving machine of the well known Koehring type.

Describing my invention in detail and referring to the drawings, A designates the loading skip of the paver or mixing machine, B the front wheels, and C shows diagrammatically the rear multiplanes or caterpillars. Projecting forwardly from the front axle 1 of the machine, on which the wheels B are mounted, are the spaced arms 2 of substantial formation, and inclining downwardly to support the cross bar 3. Attached to the opposite ends of the cross bar 3 by hinged joints 4 are the draw bars or members 5 consisting of suitable channels, or any preferred construction. The track members 5 extend some distance rearwardly 100 to points in a plane a little in the rear of the front wheels B and the rear ends of the members 5 are connected with the carrier 6, forming a part of my sub-grade planer,

or scarifier. The carrier 6 is disposed to operate transversely of the paver intermediate the front and rear traction devices for the latter.

5 The carrier 6 is comprised of a plurality of angle beams which are connected together by means of a front series of angle bars 7 disposed largely in pairs at right angles to each other or at an inclination to 10 the longitudinal plane of the machine. Also the beams 6 are connected by a rear series of scraper bars 8 which have the function of planing or scraping the surface of the sub-grade, to the desired level. The front 15 angle bars 7, carry a suitable number of scarifying teeth 9, and the scraper blades of the bars 8 may be detachable for purposes of renewal in case of wear or breakage. The scraper bars 8 have somewhat 20 the same arrangement as the bars 7 that support the scarifying teeth which operate, of course, in advance of the bars. There is a series of smaller scraper bars intermediate the bars of a series of larger scraper bars, 25 the terms smaller and larger being used in the sense particularly of length. All of said bars have an angular disposition relatively to one another, giving rise to a very efficient and desirable arrangement in regard to 30 their scraping or cutting functions.

I utilize U shaped connecting members 10 intermediate the draw bars 5 and the carrier 6. The members 10 are largely U bolts, 35 their opposite sides being threaded and attached by suitable nuts to the two foremost angle beams 6 of the carrier and in a manner which will be readily apparent. The transverse portions of the connecting members 10 are received and operate between rollers 11, on the rear ends of the draw bars 5. In this way it is evident that the means attaching the sub-grading machine of my invention to the mixer accommodates for relative transverse and vertical movement with 40 respect to the mixing or paving machine.

Near the opposite ends thereof the two rearmost angle beams of the carrier 6 have rollers 12 which are disposed so as to engage the inner sides of road forms or rails 13 seen 50 best in Figures 1 and 2. The rollers 12 form anti-friction devices between the carrier 6 and the road forms 13. Also it is to be observed that the opposite extremities of the angle beams of the carrier 6 engage over 55 and freely slide on the tops or heads of the forms or rails 13. If desired the rollers 12 may be adjustable and anti-friction rollers 60 might also be interposed between the tops of the road forms 13 and the extremities of the carrier 6 aforesaid.

It is clear that as the paver advances in its operation to load aggregates into the mixer, mix the aggregates, and dump the aggregates on the sub-grade as concrete, the 65 sub-grading planer and scarifier of my in-

vention operates in advance of the rear traction devices C, and levels the sub-grade in the required well known manner.

Having thus described my invention, what I claim as new and desire to secure 70 by Letters Patent is:

1. In combination, a sub-grade paving machine, and a sub-grade scraping device connected with said machine, track means for the paving machine, and propelling devices for said track means, a draw bar means intermediate the scraping device and the paving machine for advancing the scraping device with the paving machine, and means whereby to permit relative movement 75 between the paving machine and the scraping device, as the two operate over the sub-grade.

2. A road scraper or planer comprising a cross beam, rearwardly extending draw bar 85 members hinged thereto, a carrier comprising transverse angle beams, angle bars and scraper blades connecting said angle beams, scarifier teeth mounted on the angle bars in advance of the scraper blades, connecting members at the front portion of the carrier, rollers engaging said connecting members and supported on the rear ends of the draw bar members, thereby permitting relative movement of the carrier and draw bar 90 members, said carrier being provided with engaging portions at its ends to cooperate with road forms or rails.

3. A road scraper or planer comprising a cross beam, rearwardly extending draw bar 100 members hinged thereto, a carrier comprising transverse angle beams, scraper blades connecting said angle beams, connecting members at the front portion of the carrier, rollers engaging said connecting members and supported on the rear ends of the draw bar members, thereby permitting relative movement of the carrier and draw bar members, said carrier being provided with engaging portions at its ends to cooperate with 105 road forms or rails.

4. In combination, a portable paving machine adapted to be advanced over a sub-grade, and a road scraper for leveling the sub-grade attached to said paving machine, the attachment means comprising draw bar means carried by the paving machine, and an operative connection between said draw bar means and the scraper, constructed to permit transverse movement of the scraper 115 relatively to the paving machine, as the scraper is drawn forward by the paving machine.

5. In combination, a paving machine and propelling means therefor, a sub-grade scraper disposed transversely of the paving machine, and adapted to operate in a transverse position upon a road sub-grade, draw bar means carried by the paving machine, and a connection between said draw bar 125 130

means and the scraper comprising laterally movable members engaging the draw bar means, and adapted to permit transverse shifting of the scraper relatively to the paving machine, with anti-friction means intermediate the draw bar means and said connecting means.

6. In combination, a portable road paving machine, a sub-grade scraping machine,

attachment means for said machines comprising draw-bar means carried by one of said machines, and means between said draw-bar means and the other of said machines whereby to permit transverse and vertical movement therebetween, as the two operate over the sub-grade. 10 15

In testimony whereof I affix my signature.
JAMES M. GARVEY.
